UNITED STATES PATENT OFFICE.

LEWIS L. FOSTER, OF GOVANS, MARYLAND, ASSIGNOR OF ONE-HALF TO JOHN H. RUEHMLING, OF BROOKLYN, NEW YORK.

AIR-COMPRESSOR.

1,272,651.

Specification of Letters Patent. Patented July 16, 1918.

Application filed September 27, 1917. Serial No. 193,569.

To all whom it may concern:

Be it known that I, LEWIS L. FOSTER, a citizen of the United States, residing at Govans, in the county of Baltimore and 5 State of Maryland, have invented certain new and useful Improvements in Air-Compressors, of which the following is a specification.

This invention relates to an improved air 10 compressor and has as its primary object to provide a device of this character wherein each charge of air drawn in will be initially compressed and then subsequently recompressed before being discharged by 15 the device.

The invention has as a further object to provide a compressor employing primary compression chambers for initially compressing the air as it is drawn into the device 20 and also employing secondary compression chambers for then subsequently compressing the air and discharging the compressed air from the device.

A still further object of the invention is 25 to provide a compressor wherein a single sleeve valve will be employed to control the intake and discharge of air into and from both the primary and secondary compression chambers.

30 And the invention has a further object to provide a compressor of the above described character which will be double acting so that a charge of compressed air will be discharged from the device at each stroke 35 of the piston employed.

Other and incidental objects will appear as the description proceeds and in the drawings wherein I have illustrated the preferred embodiment of the invention and wherein 40 similar reference characters designate corresponding parts throughout the several views:

Figure 1 is a vertical sectional view of my improved compressor showing the piston of 45 the device at the top of its stroke,

Fig. 2 is a similar view showing the piston at the bottom of its stroke,

Fig. 3 is a vertical sectional view showing the connections between the piston and 50 the drive shaft of the device,

Fig. 4 is a transverse sectional view taken on the line 4—4 of Fig. 2 and looking in the direction of the arrows, this view particularly illustrating the spider employed

for supporting the inner cylinder of the 55 compressor,

Fig. 5 is a transverse sectional view taken on the line 5—5 of Fig. 2 and looking in the direction of the arrows, this view showing the exhaust port for the upper secondary 60 compression chamber of the device, and

Fig. 6 is a transverse sectional view taken on the line 6—6 of Fig. 2 and looking in the direction of the arrows, this view particularly showing the intake port for the 65 upper secondary compression chamber.

In carrying out the invention, my improved air compressor is formed with a crank case 10 through which is journaled a crank shaft 11 having cranks 12 extending 70 in the same direction and equipped at one extremity with a belt wheel or pulley 13, over which may be trained a suitable belt for driving the compressor. It will, of course, be understood that a prime motor may be 75 connected with the shaft 11 in any other suitable manner.

Mounted upon the crank case 10 is an up-standing outer cylinder 14 formed at its lower end with an annular flange 15 to 80 which is connected a closure plate 16 secured to the said flange by bolts or other suitable fastening devices which also act to connect the cylinder with the crank case. Projecting from the plate into the crank 85 case is an arm or web 17 formed at its lower end with a journal receiving the crank shaft 11. Arranged concentrically within the upper extremity of the cylinder 14 is an inner cylinder 18 closed at its lower end by a removable cap 19. Screw threaded into the upper extremity of the said cylinder is a hollow packing plug 20 formed with an axial sleeve 21 terminating at its upper extremity in an extension 22. Screw threaded 95 upon this extension is a spider 23 having, as particularly shown in Fig. 4 of the drawings, a plurality of radial arms 24. These arms overhang the upper end of the cylinder 14 and seat upon an annular flange 25 100 carried by the adjacent terminal of the said cylinder. Connecting the said arms with the flange are bolts or other suitable fastening devices 26. The spider 23 will thus rigidly support the cylinder 18 within the 105 cylinder 14 and locking the spider upon the plug 20, are a plurality of bolts or other suitable fastening devices 27.

Slidably fitted between the inner and outer cylinders 14 and 18 is a sleeve valve 28 closed at its lower end by a removable cap 29. This valve is, at its upper extremity, 5 formed with a plurality of longitudinally extending slots 30 to slidably receive the arms 24 of the spider 23 which therefore acts to lock the sleeve valve against rotation, and screw threaded into the upper extremity 10 of the said valve is a head 31. This head is formed upon its inner side with an axial boss 32 and screw threaded into this boss is the rod 33 of a piston 34 mounted to reciprocate within the cylinder 18 and having the 15 rod 33 thereof slidably received through the sleeve 21 of the packing plug 20. The piston rod 33 is equipped with suitable packing rings 35 to bear within the said sleeve, while the piston 34 is equipped with similar rings 20 36. Also, the cylinder 18 and sleeve valve 28 are equipped with suitable packing rings 37, as may be found necessary.

Arranged upon the head 31 of the sleeve valve 28 are spaced bearings 38 through 25 which is journaled a cross pin 39. Swingingly mounted upon the extremities of this pin are connecting rods 40 which project through suitable openings 41 in the crank case 10 and, at their lower ends, are secured 30 to the cranks 12 of the crank shaft 11. Consequently, rotation of the belt wheel 13 to drive the shaft 11 will simultaneously reciprocate the sleeve valve 28 and piston 34. At opposite sides of the openings 41, the 35 crank case is formed with under-cut flanges 42 and slidably mounted between the said flanges are closure plates 43 for the said openings. These plates loosely receive the connecting rods 40 to move therewith and 40 will prevent the splashing of oil from the crank case 10 through the openings 41.

As will now be best observed upon reference to Fig. 1 of the drawings, a primary compression chamber 44 is provided within 45 the cylinder 14 below the lower end of the sleeve valve 28. A second primary compression chamber 45 is provided within the said sleeve valve below the lower end of the cylinder 18. Moreover, a secondary compression chamber 46 is provided within the cylinder 18 above the piston 34, while a second secondary compression chamber 47 is provided within the said cylinder below the piston. Formed through the lower extremity of the 50 cylinder 14 at one side thereof is an intake port 48 in which is mounted a screened fitting 49. Leading through the opposite side of said cylinder from the lower end of the compression chamber 44 is a passage 50 which 55 enters through the cylinder 18 and forms, as shall presently appear, an intake passage for the secondary compression chamber 46. The sleeve valve 28, at its lower extremity, 60 is provided upon one side thereof with an internal passage 51 adapted to be brought 65

into register with a port 52 leading into the lower secondary compression chamber 47. The port 52 opens through the cylinder 14 to also provide, as shall presently appear, an exhaust port for the chamber 47. Entering 70 through the cylinders 14 and 18 at a point above the port 52, is an exhaust port 53 communicating with the upper secondary compression chamber 46. Fitted in the outer ends of the said exhaust ports and screw threaded upon the cylinder 14 is a manifold 54 from which leads a compressed air pipe 55. The port 48 is arranged out of alignment with the ports 52 and 53. Formed through the lower extremity of the sleeve valve 28, 80 upon one side thereof, is an intake port 57 adapted to register with the intake port 48. This valve is further provided with vertically spaced exhaust ports 58 and 59. The ports 58 and 59 are arranged in the same 85 vertical plane with the ports 52 and 53. Formed through the sleeve valve at the side thereof opposite the exhaust ports of the said valve, is an intake port 60.

It will now be assumed that the drive 90 wheel 13 has been rotated to shift the piston 34 upwardly from the position shown in Fig. 2 of the drawings, to the top of its stroke, as illustrated in Fig. 1. Upward movement of the sleeve valve 28 with the 95 piston will create a partial vacuum within the lower primary compression chamber 44 so that as soon as the lower end of the said valve passes over the intake port 48, a charge of air will be drawn into the said chamber. Downward movement of the piston 34 from 100 the position shown in Fig. 1, to the bottom of its stroke, as shown in Fig. 2, will then cause the valve to initially compress the charge of air within the chamber 44, and at 105 the same time create a partial vacuum within the primary compression chamber 45. When the piston has reached the bottom of its stroke, the intake port 57 will be brought 110 into register with the port 48 so that a charge of air will then be drawn into the said chamber 45. At the same time, the intake port 60 of the valve will be brought into register with the passage 50 so that the compressed charge of air within the primary compression chamber 44 will be forced 115 by the said valve through the said passage and into the upper secondary compression chamber 46. The piston, upon again moving upwardly, will therefore again compress the 120 charge of air within the chamber 46 received from the chamber 44 while, at the same time, the valve 28 will initially compress the charge of air drawn into the secondary compression chamber 45. When the piston has 125 reached the top of its stroke, the discharge passage 58 of the valve will be brought into register with the discharge port 53, when the doubly compressed charge of air within 130 the upper secondary compression chamber

- 46 will be forced by the piston out through the pipe 55. At the same time, the passage 51 of the valve will, as shown in Fig. 1, be brought into register with the inner portion 5 of the passage 52 so that the compressed charge of air within the primary compression chamber 45 will be forced into the lower secondary compression chamber 47. Therefore, the piston, upon again moving downwardly, will again compress this charge of 10 air within the chamber 47 while the valve 28 will as previously described, initially compress a charge of air within the chamber 44. When the piston has again reached the bottom of its stroke, the discharge port 59 of the valve will be brought into register with the discharge port 52 so that the doubly compressed charge of air within the secondary compression chamber 47 will be 15 forced by the piston out through the pipe 55. At the same time, the compressed charge of air within the chamber 44 will, as previously described, be admitted to the upper secondary compression chamber 46. 20
- 25 It will therefore be seen that the device will thus continuously operate to draw in, each time the piston moves upwardly, a charge of air within the primary compression chamber 44, to initially compress a 30 charge of air within the primary compression chamber 45 and to recompress a charge of air within the upper secondary compression chamber 46. In like manner, each time the piston moves downwardly, a charge of 35 air will be initially compressed within the chamber 44, a charge of air will be drawn into the chamber 45, and a charge of air will be recompressed within the chamber 47. Each charge of air drawn in by the device 40 will thus be initially compressed and will then again be subsequently recompressed while at the same time, a charge of air will be discharged from the device at each stroke of the piston to thus render the compressor 45 double acting. Furthermore, it will be noted that the intake and exhaust of air into and from both the primary compression chambers and the secondary compression chambers is controlled by a single sleeve valve 50 which also coöperates with the cylinders of the device to itself provide a piston for initially compressing the air drawn into the device. For heavy duty, the pump may be either air cooled or water cooled and since 55 such cooling may be effected in any approved manner, a cooling system for the pump has not been shown.
- Having thus described the invention, what is claimed as new is:
- 60 1. An air compressor including inner and outer cylinders, a sleeve valve slidably mounted between the said cylinders and coacting therewith to provide primary compression chambers, a piston mounted to reciprocate within the inner cylinder, the said 65 inner cylinder providing secondary compression chambers at opposite sides of said piston, an intake port for the primary compression chambers, passages for establishing communication between the primary and secondary compression chambers, and exhaust ports for the said secondary compression chambers, the sleeve valve being movable for opening and closing said passages and the 70 said ports. 75
2. An air compressor including inner and outer cylinders, a sleeve valve mounted to slide between the said cylinders and coacting therewith to provide primary compression chambers, a piston mounted to reciprocate within the inner cylinder, passages for establishing communication between the said chambers and the inner cylinder at opposite sides of the said piston, an intake port for the said chambers, and exhaust ports leading 80 from the inner cylinder at opposite sides of the piston, the sleeve valve being movable for opening and closing said passages and the said ports. 85
3. An air compressor including inner and outer cylinders, a sleeve valve mounted to slide between the said cylinders and coacting therewith to provide primary compression chambers, a piston mounted to reciprocate within the inner cylinder, passages for establishing communication between the said chambers and the inner cylinder at opposite sides of the said piston, an intake port for the said chambers, and exhaust ports leading 90 from the inner cylinder at opposite sides of the piston, the sleeve valve being movable with the piston for compressing a charge of air within one of said chambers and drawing in a charge of air within the other of said chambers and controlling communication between the chambers and the inner cylinder through said passages for admitting the compressed charge of air at one side of said piston at each stroke thereof as 95 well as controlling the opening and closing 100 of said ports. 105
4. An air compressor including inner and outer cylinders, a sleeve valve mounted to slide between the said cylinders, a piston mounted to reciprocate within the inner 110 cylinder and connected with the said valve, the valve coöperating with the cylinders to provide primary compression chambers and the inner cylinder providing secondary compression chambers at opposite sides of said 115 piston, passages for establishing communication between each of the said primary compression chambers and one of the secondary compression chambers, an intake port for the primary compression chambers, 120 and exhaust ports for the secondary compression chambers, the sleeve valve being movable for opening and closing said passages and the said ports for drawing in a 125 charge of air into one of the primary com- 130

pression chambers, for compressing a charge of air within the other of the primary compression chambers and forcing the said compressed charge into one of the secondary compression chambers and opening the exhaust port of the other of the secondary compression chambers at each stroke of the piston.

5. An air compressor including inner and outer cylinders, a piston mounted to reciprocate within the inner cylinder, exhaust ports leading from the said inner cylinder at opposite sides of the piston, a sleeve valve mounted to slide between the cylinders and coacting therewith to provide compression chambers, an intake port for the said chambers, and passages for establishing communication between the chambers and the inner cylinder at opposite sides of the said piston, 10 the sleeve valve being movable with the piston for opening and closing said passages and the said ports and for initially compressing a charge of air within one of the said chambers at one side of the piston at 15 each stroke thereof to be subsequently recompressed by the piston upon its next stroke.

6. An air compressor including inner and outer cylinders, a piston mounted to reciprocate within the inner cylinder, a sleeve valve mounted to slide between the cylinders and coacting therewith to provide compression chambers, exhaust ports leading from the inner cylinder at opposite sides of the piston, an intake port for the said chambers, and passages for establishing communication between the chambers and the inner cylinder at opposite sides of the piston, the valve being movable with the piston for 20 opening and closing said ports to permit the discharge of a compressed charge of air from the inner cylinder at each stroke of the piston and to introduce a compressed charge of air from one of the said chambers 25 into the inner cylinder at one side of the piston.

7. An air compressor including inner and

outer cylinders, a piston mounted to reciprocate within the inner cylinder, exhaust ports leading from the inner cylinder at opposite sides of the piston, a sleeve valve mounted to slide between the said cylinders and movable with the cylinders for opening one of said ports and closing the other at each stroke of the piston, said valve co-operating with the said cylinders to provide compression chambers, an intake port for the said chambers, and passages for establishing communication between the said chambers and the inner cylinder at opposite sides of the piston, the sleeve valve being also movable with the piston for drawing in a charge of air into one of said chambers, for compressing a charge within the other of said chambers, and for establishing communication between the said last mentioned chamber and the inner cylinder at one side of the piston at each stroke thereof.

8. An air compressor including inner and outer cylinders, a packing plug closing the inner cylinder, a piston mounted to reciprocate within the inner cylinder and having the rod thereof slidably received through said plug, means carried by the piston rod and co-operating with the plug to provide a tight joint between the piston rod and the plug, a sleeve valve connected with the piston and slidably mounted between the said cylinders, the said sleeve valve coacting with the cylinders to provide primary compression chambers and the inner cylinder providing secondary compression chambers at opposite sides of said piston, an intake port for the primary compression chambers, passages for establishing communication between the primary and secondary compression chambers, and exhaust ports for the said secondary compression chambers, the sleeve valve being movable with the piston for opening and closing said passages and the said ports.

In testimony whereof I affix my signature.
